Specification for Design.

Patented Apr. 28, 1914.

Application filed January 12, 1914. Serial No. 811,760. Term of patent 3½ years.

To all whom it may concern:

Be it known that I, BENNO VOM EIGEN, a citizen of the United States, residing at Newark, in the county of Essex and State of New Jersey, have invented a new, original, and ornamental Design for Vanity-Inserts for Bags, of which the following is a specification, reference being had to the accompanying drawing, forming part thereof.

The invention is clearly illustrated in the accompanying drawings, in which:—

Figures 1 and 2 are the obverse and reverse face views of the vanity insert for bags, showing my new and ornamental design; and Fig. 3 is a top-edge view of the vanity insert.

I claim:—

The ornamental design for a vanity insert for bags, as shown.

BENNO VOM EIGEN.
